Primary Examiner — W. A. Teddy Falloway(74) *Attorney, Agent, or Firm* — Womble Bond Dickinson (US) LLP**CLAIM**

The ornamental design for a carrier, as shown and described.

DESCRIPTION

FIG. 1 is a perspective view of a carrier showing our new design.

FIG. 2 is a front elevation view of the carrier of FIG. 1, the rear elevation view is a mirror image.

FIG. 3 is a left elevation view of the carrier of FIG. 1, the right elevation view is a mirror image.

FIG. 4 is a top plan view of the carrier of FIG. 1.

FIG. 5 is a bottom plan view of the carrier of FIG. 1; and, FIG. 6 is a plan view of the carrier of FIG. 1 shown in an unfolded configuration.

The broken lines showing cans illustrate environmental structure. All other broken lines represent portions of the carrier. The broken lines form no part of the claimed design.
